GRINDING AND POLISHING MACHINE

John Mason Adams, Farley, Mass.

Application June 24, 1946, Serial No. 678,816

2 Claims. (Cl. 51—135)

1

This invention relates to a novel construction of machine for use in grinding and polishing and has particular reference to a machine of the type in which a driven endless belt performs the grinding or polishing operation.

A primary object of the present invention is to provide a machine of the above described character having means to facilitate the adjustment of the various parts thereof for tensioning the grinding and polishing belt, for canting the belt with respect to the work and for raising, lowering and tilting a work support to correctly position the work for engagement by the belt.

Other objects and advantages of the invention will hereinafter become more fully apparent from the following description of the drawing, which illustrates a preferred embodiment thereof, and wherein—

Figure 1 is a side elevational view of preferred embodiment of the machine, shown partly in section;

Figure 2 is a top plan view thereof;

Figure 3 is transverse vertical sectional view taken substantially along a plane as indicated by the line 3—3 of Figure 2;

Figure 4 is an enlarged transverse vertical sectional view taken substantially along a plane as indicated by the line 4—4 of Figure 1, and

Figure 5 is an enlarged fragmentary vertical sectional view of a portion of one of the pulleys over which the grinding and polishing belt is trained.

Referring more specifically to the drawing, the machine in its entirety is designated generally 6 and includes a base 7 which is adapted to rest on a suitable supporting surface and may, if desired, be suitably secured thereto. The base 7 is provided adjacent one end thereof with an upwardly and outwardly inclined standard 8, which is secured thereto as by means of a fastening 9. The standard 8 is provided with a transverse sleeve portion 10 in which is received a bushing 11. The bushing 11 is adjustably fixed in the sleeve 10 by means of set screws 12. A shaft 13 is journaled in the bushing 11 and is provided with a protruding end on which is mounted a pulley 14. A nut 15 engages the threaded terminal of the protruding end of the shaft 13 for detachably retaining the pulley 14 in applied position. The shaft 13 may be provided with anti-friction bearing means, not shown, interposed between said shaft and the bushing 11.

A pair of guide rods 16 are supported in parallel relationship above the opposite end of the platform 7 and lengthwise thereof by posts 17 which

2

rise from the platform 7 and which engage the ends of the rods 16. The standard, designated generally 18 is provided with an enlarged base 19 having openings extending longitudinally therethrough and disposed in substantially parallel relationship. Said openings 20 are adapted to slidably receive the rods 16, as best seen in Figure 3, to mount the standard 18 for lengthwise sliding movement with respect to the base 7. The standard 18 comprises a lower section 21 and an upper section 22 having opposed faces provided with opposed arcuate grooves 23 which extend in a direction lengthwise of the machine 6 and which are engaged by a pin 24. As best seen in Figure 3, the pin 24 supports the upper standard section 22 with its bottom surface in spaced apart relationship to the top surface of the lower standard section 21.

As best seen in Figures 1 and 2 the adjacent portions of the standard sections 21 and 22 are provided with flanges 25 which project from opposite sides of the sections 21 and 22 and in directions lengthwise of the machine 6. The superimposed flanges 25 are provided with screw fastenings 26 which extend through opposite ends thereof and which engage threaded openings 27 in the lower flanges 25. It will thus be readily apparent that the screw fastenings 26 are located at diagonally opposed corners of the sections 21 and 22 and on opposite sides of the pivot pin 24, so that by loosening either of the fastenings 26 and tightening the other fastening 26, the upper standard section 22 can be tilted transversely with respect to the lower standard section 21.

A feed screw 28 is provided with a threaded portion adjacent one end thereof which extends through and threadedly engages a threaded opening 29 in the standard 8. Said threaded portion of the feed screw 28 terminates in a handle or knob 30, which is located on the outer side of the standard 8. The opposite end of the screw 28, which is unthreaded, extends through and is journaled in an opening 31 of the standard section 21. Said last mentioned end of the screw 28 is provided with a pair of collars 32, as seen in Figure 1, which engage opposite sides of the standard section 21.

The upper standard section 22 is provided with a transverse bore 33 which opens into enlarged recesses 34 formed in opposite sides of the section 22 and each of which contains an anti-friction bearing means 35 including a plurality of ball bearings and inner and outer bearing races. A shaft 36 extends loosely through the bore 33 and is provided with spaced portions which are

journaled in the anti-friction bearing means 35. The shaft 36 is provided with an enlargement or collar 37 which bears against the outer side of one of the bearing means 35 and which is provided at its outer end with a restricted threaded shank 38 to receive a belt pulley 39 which is detachably clamped thereon by a nut 40 and which is disposed substantially in longitudinal alignment with the belt pulley 14. The opposite end of the shaft 36 protrudes from the opposite side of the standard section 22 and is splined or keyed to a belt pulley 41. The shaft 36 is preferably provided with a washer or narrow collar 42 which is located between the pulley 41 and the adjacent bearing means 35. The belt pulley 41 is driven by an endless belt 43 which is trained thereover and driven by suitable driving means, not shown, for revolving the shaft 36 and the belt pulley 39.

An endless abrasive or polishing belt 44 is trained over the belt pulleys 14 and 39 and is driven by said pulley 39, with the pulley 14 acting as an idler pulley. As illustrated, the pulley 39 is substantially larger in diameter than the pulley 14, but it is to be understood that the relative diameter of the two pulleys may be varied. The belt pulleys 14 and 39 each includes an inner or hub portion 45 which may be formed of metal of any other suitable material and a rim portion 46 which is disposed around the periphery of the inner portion 45 and which is preferably formed of synthetic rubber, and which is provided with a plurality of outwardly opening circumferential extending grooves 47. The synthetic rubber rims or tires 46 are employed on the belt pulleys 14 and 39 for engagement with the abrasive belt 44; it having been discovered that synthetic rubber may be more readily formed on the belt pulleys than natural rubber and is more practical for use in connection with an abrasive belt. The grooves 47 are provided to afford better traction for the belt 44 and the thickness of the tire or rim portion 46 may be varied depending upon the type of work for which the belt is being utilized. The belt 44 may be formed of any suitable abrasive material, the fineness of which may vary or may be impregnated, coated or have an abrasive material otherwise applied thereto. Further, the belt 44 may be dressed with tallow or paraffin wax to eliminate the collection of dirt and foreign matter behind the grain thereof.

The base 7 is also provided with two upstanding standards 48 and 49 which are disposed intermediate of the ends thereof and in longitudinally spaced relationship to one another. The standard 48 is secured as by welding 50 at its lower portion to the upper side of the base 7. The standard 49 is provided with an elongated base portion 51 having a downwardly opening longitudinally extending groove 52 in which is slidably received the upper end of a pin 53. The pin 53 is anchored in the base 7, as seen in Figure 1. The base portion 51 is also provided with an elongated slot 54 through which a threaded bolt 55 extends. The bolt 55 engages a threaded opening or recess 56 in the base 7 and is adapted to be tightened to function in connection with the pin 53 to fixedly position the standard 49 relatively to the base 7. However, it will be readily apparent that the bolt 55 may be loosened to enable the standard 49 to be moved lengthwise of the base 7 toward and away from the standard 48.

Each of the standards 48 and 49 is provided with an upwardly opening bore 57 for detachably

and adjustably receiving the lower end of a rod or leg 58. The legs or rods 58 are detachably and adjustably retained in the bores 57 by set screws 59 which are adjustably mounted in the upper portions of the standards 48 and 49 and transversely thereof and which extend into said bores 57.

A table or platform 60 is provided with depending bifurcated brackets 61 which are located adjacent one edge thereof and which are connected to the upper ends of the legs or rods 58 by pivot pins 62 which extend therethrough for pivotally mounting the table top 60 on the rods 58, as best illustrated in Figure 4. The table top 60 includes top and bottom plies 63 and 64, respectively, which may be formed of any suitable material and an intermediate ply 65 which is preferably formed of synthetic rubber. As seen in Figure 2, the plies 63, 64 and 65 are connected adjacent the corners of the table top 60 by fastenings 66.

The rods or legs 58 are located inwardly of the belt 44 and between the screw 28 and the lower flight of said belt and are pivotally connected to the table top 60 along its inner longitudinal edge to position said table top between the top and bottom flights of the grinding or polishing belt 44.

The work to be ground or polished is placed on the upper surface of the table or platform 60 and may be suitably held or clamped thereto to be engaged by the inner, abrasive side of the upper flight of the driven abrasive or polishing belt 44. The table top 60 may be raised or lowered relatively to the upper flight of the belt 44 by loosening the set screws 59, adjusting the rods 58 in the bores 57 and thereafter tightening said set screws for correctly positioning the work, not shown, supported on the table top 60 for engagement by the belt 44. Further, the table top 60 may be tilted in a direction lengthwise of the machine 6 by vertically adjusting one of the rods or legs 58 relatively to the other and as such adjustment will cause the rods 58 to be moved toward or away from one another, the screw 55 may be loosened to permit adjustment of the standard 49 toward and away from the standard 48 to compensate for this movement of the rods 58. Likewise, and as previously described, the fastenings 26 can be adjusted for 45 tilting the standard section 22 and the shaft 36 laterally to cant the belt 44 so that by thus adjusting the table top 60 and belt 44, a substantial universal adjustment of the work with the abrasive belt may be obtained. It will be readily apparent that the screw 28 is adjusted for tensioning the belt 44 and may also function for varying the tension of the driving belt 43.

Various modifications and changes are contemplated and may obviously be resorted to without departing from the spirit and scope of the invention as hereinafter defined by the appended claims.

I claim:

1. In a grinding and polishing machine, a base, spaced standards rising from the base, a shaft journaled in each of said standards, a belt pulley keyed to each of said shafts, an endless abrasive belt trained over said belt pulleys, one of said shafts being driven for driving the endless abrasive belt, a work support attached to and rising from said base and including a platform or table located between the upper and lower flights of said abrasive belt for supporting a piece of work to be engaged by the inner side of the upper flight 75 of the abrasive belt, said work support being

adjustable for varying the elevation of said platform or table top to move it toward or away from the upper flight of the abrasive belt and for tilting said table top in a direction lengthwise of the belt, and adjustable means for tilting one of said belt pulleys for canting the belt flights relatively to the table top.

2. In a grinding and polishing machine, a base, spaced standards rising from the base, a shaft journaled in each of said standards, said shafts being disposed substantially parallel, a belt pulley keyed to each of said shafts, an endless abrasive belt trained over said belt pulleys, one of said shafts being adapted to be driven for driving the endless abrasive belt, a work support attached to and rising from said base and including a platform located between the upper and lower flights of said abrasive belt for supporting a piece of work to be engaged by the inner side of the upper flight of the abrasive belt, and one of said standards having an upper section in which one of the shafts is journaled and which section is mounted for rocking movement about an axis disposed parallel

to the longitudinal axis of the belt to rock the shaft carried thereby in a vertical plane for canting the belt relatively to the platform.

JOHN MASON ADAMS.
